UNITED STATES PATENT OFFICE.

CHARLES H. PATTEN, OF PROVIDENCE, RHODE ISLAND, ASSIGNEE TO REX MANUFACTURING COMPANY, OF PROVIDENCE, RHODE ISLAND, A CORPORATION OF RHODE ISLAND.

EXTENSION DEVICE FOR FLEXIBLE BRACELETS.

Application filed December 11, 1926. Serial No. 154,117.

This invention relates to an extension device for flexible bracelets more especially wrist watch straps to be unfolded for the purpose of extending the operating length 5 of the strap and the object of the invention is to provide a plurality of sections of an inexpensive construction which are pivoted together at one end and have a releasable frictionally operated attachment at their 10 opposite end.

A further object of the invention is to provide a releasable securing means at the free ends of the sections by integral formations on the sections which cooperate to 15 snap one over the other in a direction longitudinally of the device.

A still further object of the invention is the provision of a lateral extension on the plate section and cooperating receiving 20 means in the walls of a channel section into which said extension may be snapped to secure the sections in folded position.

With these and other objects in view, the invention consists of certain novel features 25 of construction, as will be more fully described, and particularly pointed out in the appended claims.

In the accompanying drawings:

Figure 1 is a side elevation showing my 30 improved extension device in its working position in a watch bracelet strap.

Figure 2 is a perspective view of the channel section.

Figure 3 is a perspective view of the plate 35 section.

Figure 4 is a side elevation of the device in assembled position showing the undercut end of one of the side walls of the channel section which is adapted to be snapped over 40 a portion of the plate section to releasably secure the sections together.

Figure 5 is a plan view of the sections in folded position.

Figure 6 is a sectional view on line 6—6 45 of Figure 1.

Figure 7 is a perspective view of the device in unfolded position with portions of the wrist watch strap attached.

Figure 8 is a perspective view showing a 50 modified form of releasable engagement between the free ends of the sections.

It is found desirable to provide a connecting device interposed between the ends of a wrist watch strap of such construction

that the same may be unfolded to temporarily lengthen the bracelet and permit the same to be passed over the hand of the wearer to and from position on the wrist and in order to provide such a device of simple and inexpensive construction I have 60 provided one member channel shape in cross section and the other member of sheet metal formation with integral trunnions pivotally supported in such walls of the channel section, and I have provided suitable formations between the end of the wall of the channel section, such as undercutting or recessing the same and cooperating lateral extensions on the plate section to snap beneath these undercut or into the recess portions to frictionally releasably retain the device in folded position; and the following 70 is a detailed description of the present embodiment of this invention and showing one means by which these advantageous results 75 may be accomplished:

With reference to the drawings, 10 designates the channel section having side walls 11 with openings 12 adjacent one end thereof in which laterally extending trunnions 13 80 are pivotally mounted, the opposite ends of the side walls 11 are under cut as at 15 and lateral extensions 16 on the plate section 14 are so positioned that they will snap beneath and be retained 85 in these undercut portions 15, as illustrated in Figure 4 to retain the sections of the device in folded position.

In order that the trunnions 13 may be easily positioned in the openings 12 of the 90 side walls 11, I have slotted as at 17 the stock of the section 10 adjacent each of the side walls so that these walls will be more resilient and spread sufficiently to receive the trunnions 13.

At the free end of each of the sections slots 18 and 19 are formed through which the straps 20 and 21 of the watch bracelet may be passed and suitably secured, it being apparent that the strap 21 lies over the convex side of the section 14 when the same is in folded position and thus to a considerable extent hides the extension device.

It will be apparent that the sections are slightly concaved in form to fit the wrist 105 of the wearer and that the device is extremely simple in construction and yet durable and effective in its operation.

The foregoing description is directed solely towards the construction illustrated, but I desire it to be understood that I reserve the privilege of resorting to all the 5 mechanical changes to which the device is susceptible, the invention being defined and limited only by the terms of the appended claims.

I claim:

- 10 1. An extension device for a flexible bracelet comprising a pair of sheet metal sections, each having a slot adjacent one end and hingedly connected together at their opposite ends, integral lateral projections extending 15 from one of said sections and formations on the other of said sections to snap behind said lateral projections by resiliency in a longitudinal direction of one of said sections and retain the sections in closed position.
- 20 2. An extension device for a flexible bracelet comprising a channel-shaped section having side walls, a plate section having integral laterally-extending trunnions at one end piv-

oted in said side walls, integral laterally-extending projections at the opposite end of said plate section, said side walls adjacent their free ends having portions so formed as to snap behind said laterally-extending projections by longitudinal resiliency of one 30 of said sections to releasably retain the sections in folded position, and means associated with each of said sections for attaching a strap thereto.

3. An extension device for a flexible bracelet comprising a channel-shaped section having side walls undercut at one end, a plate section having integral laterally-extending trunnions at one end pivoted in said side walls, laterally extending projections at the 40 opposite end of said plate section positioned to be engaged by the undercut ends of said side walls to releasably retain the sections in folded position, and means associated with each of said sections for attaching a strap 45 thereto.

In testimony whereof I affix my signature.

CHARLES H. PATTEN.
